PROCESS OF TREATING FUR

Isadore Reiffel, Mount Vernon, N. Y.

Application June 5, 1935, Serial No. 24,999

6 Claims. (Cl. 149—28)

This invention relates to a process of treating fur, being particularly applicable to beaver and nutria for making such skins more presentable, lighter and less expensive.

5 It is known in the fur industry that there is relatively little demand for beaver as an appurtenance to wearing apparel due to certain properties that are inherently characteristic of that fur. Garments made therefrom are known to be large, 10 heavy and bulky, and not as attractive in appearance as the more expensive furs. Particularly when it becomes wet does it lose whatever attractive properties it may possess due to the fact that the long fur hair is subject to a curling tendency 15 under such conditions. Furthermore, beaver and nutria contain certain long coarse guard hair interspersed between the fine fur hair resulting in a surface bespecked with many shiny spots. It is hence for the purpose of eliminating these disadvantages characteristic of such skins that I 20 have conceived this invention, which is for a process of treating or dressing such furs to reduce their weight for convenient wearing purposes, to prevent curling of the fur and thereby avoid the resulting shabby appearance thereof when wet; and to further beautify such pelts by eliminating the unsightly guard hair, exposing to view the 25 lighter colors near the underwool of a beaver skin to produce a striped effect, giving a higher gloss to the fur surface and imparting a velvet-like texture thereto,—all of which constitute some of the objects of my invention. Other objects, 30 features and advantages will appear from the description of the process hereinafter given.

35 Although this invention contains steps specifically directed to accomplish the above-mentioned objects, they may be combined with other commonly known steps employed in the ordinary dressing of fur; and hence in the description 40 hereinafter given certain steps not entirely necessary are referred to merely to clarify the nature of the entire process and help in the description thereof.

The drawing forming a part of this application constitutes a flow sheet showing the essential steps of the process of my invention.

45 As applied to beaver, the first objective of my invention is to remove the coarse guard hairs,—this being accomplished by plucking or pulling them out by the roots. To properly prepare the fur for this step, the raw pelts are soaked until soft and then put into a centrifugal extractor to wring out the solution. Thereafter they are drummed with saw-dust until about three-fourths dry, after which they are run in a re-

volving cage to remove the saw-dust. The beavers are then folded up and hung in a dry room so that the hair will dry, but the leather remain partially moist. When they are removed from the dry room, the hair is powdered with chalk or whiting, placing the pelts in condition for the plucking operation.

The step of plucking is accomplished by placing the skin on a beam and operatively applying to the fur thereof a heavy dull-edged curved knife, 10 thereby pulling out most of the relatively stiff, accessible guard hair from the fur. Although this is the preferred method of performing the first plucking operation, other methods can be employed within the scope of this invention. It 15 should be noted that this operation is considerably facilitated by the previous step of powdering, inasmuch as the chalk or whiting increases the effective frictional grip of the plucking tool upon the hair which, if uncoated, might be too 20 smooth for operative efficacy.

The fur is then put through a dressing process including the steps of removing the chalk, soaking the skins until soft, wringing out the solution in an extractor, cutting away surface fat, meat, 25 etc., and if necessary, again soaking the skin and extracting the solution as heretofore until it is almost dry. Thereafter in accordance with one form of practicing my invention, the combined tanning operation and "egg yolk" treatment is 30 performed, which includes the step of placing the skin into a water-tight revolving drum containing tanning chemicals to which is added a small quantity, generally 1%, of what I call an "egg yolk" solution, comprising 80% salt free egg yolk, 35 10% glycerin and 10% castor oil,—these percentages being by volume, the proportions being approximate and subject to variation in accordance with conditions. This solution is added for the purpose of giving beaver or nutria a high 40 gloss, and for the further purpose of preparing the leather for the shaving operation which will hereinafter be described as another step in my process to produce a paper-like thinness thereof without injuring the fur. To further prepare the 45 skin for the shaving operation, it is wrung out in an extractor, dried, run in saw-dust drums until it becomes pliable, and then the saw-dust is removed by rotating the skin in a revolving cage. It should be noted that in the tanning process 50 hereinabove mentioned, various agents may be employed,—a suitable formula comprising salt, alum, sal ammoniac and sal soda in various proportions depending upon conditions.

When the fur is thus prepared, it is ready for 55

the combined leather shaving and stretching operation. By using preferably a machine consisting of cylindrically mounted blades, as long as the width of the skin, the leather is shaved down to a predetermined thickness,—the previous preparing operation enabling an extremely light-weight pelt to be obtained. As the leather is being thus shaved, the skin is being simultaneously stretched, thereby not only helping the shaving operation but producing a larger and lighter skin.

The skins are thereafter prepared for a second shaving operation, by greasing the leather with mineral oils and animal fats, mechanically pounding these oils and fats into the leather, revolving the skins in saw-dust drums until the surface grease is absorbed but permitting the grease in the leather to be retained therein. The saw-dust is then removed and the solution of soap and water applied to the leather side of the skin, after which the pelt is in condition for the second shaving operation.

The completion of the last preparing operation now permits the second shaving step to be performed to cut the leather down to an exceedingly fine thickness,—the operation being preferably though not necessarily performed on a circular shaving machine. Although I prefer a circular machine for this step, any other leather slicing method may be employed within the scope of this invention.

After further drummings of the fur and the removal of the dust therefrom if it is considered necessary to further clean same and render the leather more soft and pliable, the skins are prepared for a subsequent operation which will hereinafter be referred to as unhauling. One of the essential steps in preparation thereof consists of the operation of beating up the fur preferably with heavy reed sticks, to make the coarse hair more visible. By this step the hairs and fur are loosened up, and folded up or covered guard hair caused to stand up so as to be exposed for the next step.

When this is completed, the unhauling operation is performed, consisting of the step of cutting off the coarse guard hairs at their roots, so as not to be visible, or discernible by touch through the soft fine fur. This operation may be done either by machine or by hand, the specific step rather than the specific means being an element of this invention.

The next important step is that of shearing, or cutting the fur to such predetermined height as is considered expedient by experience. A special shearing machine is preferably employed for this purpose consisting of a plurality of cylindrically disposed blades set at an angle and cooperating with a stationary knife set close thereto, the revolution of the cylinder producing a shearing action. This operation, as stated, shortens the fur, reduces the weight of the pelt as a result thereof and also, when applied to beaver, exposes the lighter underwool at the roots of the fur to produce a striped effect not ordinarily seen in the usual heavy beaver skins.

At this stage it is possible that not all the fur has been sheared to a uniform height due to the fact that some of the fur hairs may have been bent over during the shearing process, permitting the blades to pass thereover without cutting them. To prepare the skin for a reshearing operation, the skins are given a very careful drumming with saw-dust to which is added preferably rice starch in the approximate proportion of one

part by weight of starch to eight parts of saw-dust,—the rice starch having the effect of stiffening the tops of the fur hairs so as to render them more susceptible to the action of the cutting tool in the next shearing step, it being understood that other hair stiffening means may be employed within the contemplation of my invention.

Thereafter the beavers are glazed or electrified,—a process which is effected by applying a heated iron and brushes alternately to the fur,—the heat adding to the lustre thereof and the brushing straightening out the hairs to disclose any omissions or irregularities in the above-mentioned unhauling and shearing steps.

The last important step in the process is the reshearing operation, similar to the shearing step above described, but repeated for removing any high spots disclosed by the glazing operation, and making the fur more uniform, to produce a smooth, even and velvet-like texture.

It is of course obvious that beaver or nutria processed by my invention will not only be lighter in weight, but more beautiful in appearance for reasons already set forth. Furthermore, inasmuch as the fur treated by this process is much shorter, the curling tendencies heretofore considered inherently characteristic of beavers when exposed to moisture are entirely eliminated.

The process constituting my invention may contain all of the steps above mentioned, or where experience dictates otherwise, certain of the steps may be omitted,—depending upon the nature of the skin, the section of the country from which it came, the season it was pelted and other considerations. The important steps, however, namely plucking, shaving, unhauling, shearing and reshearing are necessary in practically every case where this process is to be applied to previously untreated beaver or nutria, in view of the fact that these steps are directed to reducing weight, shortening the hairs and removing the unsightly guard hairs. Where, however, certain of the steps are unnecessary, due to a previous processing or the very nature of the skin, certain parts of this process can independently be employed to perform the functions intended for them, such as treating a skin merely to remove the guard hair, or to reduce the height of the fur hairs,—all without employing the other steps of the process.

It is of course understood that modifications of the steps and departures from the specific procedure hereinbefore outlined may be resorted to within the scope of the appended claims, without departing from the spirit of this invention.

What I claim is:

1. In a method of treating beaver, the steps of drumming the skin in a mixture of one part of rice starch and eight parts of saw-dust to stiffen the tops of the fur, and shearing the fur to a predetermined height.

2. In a method of treating a beaver fur skin and the like, the steps of operatively applying a mixture of rice starch and saw-dust to the fur to stiffen the tops thereof, and shearing the fur to a predetermined height.

3. In a method of treating a fur skin, the steps of operatively applying rice starch to the fur to stiffen the tops thereof, and shearing the fur to a predetermined height.

4. In a method of treating a fur skin, the steps of stiffening the tops of the fur hairs, and shearing the fur to a predetermined height.

5. In a method of treating a beaver fur skin

and the like, the steps of shearing the fur to a predetermined length, stiffening the fur, brushing the fur to straighten up unsheared furs, and reshearing the fur to level it off and further reduce 5 the height thereof.

6. In a method of treating a fur skin, the steps of cutting off the guard hairs, shearing the fur

to a predetermined length, drumming the skin with a mixture of sawdust and rice starch to stiffen the tops of the furs, brushing the fur to straighten up unsheared furs, and reshearing the fur to level it off and further reduce the height 5 thereof.
